FOLDING CHAIR

David Woods, Quakertown, Pa., assignor to J. G.
Furniture Company, Inc., New York, N.Y.

Filed Mar. 24, 1971, Ser. No. 127,865

Term of patent 14 years

Int. Cl. D6—02

U.S. Cl. D6—41

FIG. 1.

FIG. 2.

FIG. 3.

FIG. 4.

FIG. 6.

FIG. 7.

FIG. 1 is a perspective view of a folding chair embodying my new design with the seat opened;

FIG. 2 is a front elevational view of the opened folding chair of FIG. 1;

FIG. 3 is a top plan view of the opened folding chair of FIG. 1;

FIG. 4 is a rear elevational view of the opened folding chair of FIG. 1;

FIG. 5 is a side elevational view of the opened folding chair of FIG. 1;

FIG. 6 is a side view similar to FIG. 5 of the folding chair of FIG. 1 with the seat closed; and

FIG. 7 is a side elevational view similar to FIG. 5 of a modification of the folding chair of FIG. 1, other

views thereof being similar to FIG. 1 through FIG. 6 but with the modification thereto shown in FIG. 7.

I claim:

The ornamental design for a folding chair, as shown and described.
